UNITED STATES PATENT OFFICE.

JOSEPH P. LA ROCHE, OF CHICAGO, ILLINOIS.

MUSIC ROLL, PURSE, AND CARRYING BAG.

1,426,485.

Specification of Letters Patent. Patented Aug. 22, 1922.

Application filed November 15, 1920. Serial No. 424,283.

To all whom it may concern:

Be it known that JOSEPH P. LA ROCHE, a citizen of the United States of America, residing at Chicago, county of Cook, and State 5 of Illinois, has invented a new and useful Music Roll, Purse, and Carrying Bag, of which the following is a specification.

The purpose of the present invention is to provide an improved music roll, purse and carrying bag including a closure and fastening means, which are common to the music roll, purse and carrying bag when used respectively as such.

As a further purpose it is the aim to provide a device of this kind comprising inner, outer and intermediate sections joined by means of bellows connections, thereby providing compartments, in which articles may be supported, when used as a carrying bag, 10 and when the device is folded so that it can be used as a music roll, half portions of the compartments may be used as purse compartments, there being a thickness of material, such as leather or the like preferably 15 the former secured to a portion of the intermediate member of the roll, purse or carrying bag, so as to provide a compartment for change and paper currency, the closure 20 acting as means common to the purse and music roll or closing both of them.

Another purpose resides in the provision of a stiffening member secured between a lining and the material of the closure longitudinally of the upper part of the music roll, 25 purse and carrying bag, so as to afford means for attaching a carrying handle in place.

It is obvious that any suitable fastening 30 means, such as snap fasteners or the like may be carried by the closure and the upper portion of the inner thickness of the device and the lower portion of the outer thickness, so that the closure may close the carrying bag if employed as such, when so closing the purse or music roll.

It is also obvious that when the device is 35 used as a music roll, it is possible to use it as a purse at the same time, as the music may only be folded and placed between the folded parts of the device when used as a purse.

While the design and construction at present illustrated and set forth is deemed preferable, it is obvious that as a result of a reduction of the invention to a more practical form for commercial purposes, the invention 40 may be susceptible of changes, and the right to these changes is claimed, provided

they are comprehended within the scope of what is claimed.

The invention comprises further features and combination of parts, as will be herein-after set forth, shown in the drawings and claimed.

In the drawings:

Figure 1 is a view in perspective of the combined music roll, purse and carrying bag, 45 showing the same folded and used as a combined music roll and purse and constructed in accordance with the invention.

Figure 2 is a view in perspective showing the combined purse and music roll partly 50 open, more clearly showing the construction and arrangement of the parts.

Figure 3 is a perspective view showing the device used as a carrying bag with the closure fastened.

Figure 4 is a sectional view on line 4—4 of Figure 1.

Figure 5 is a sectional view on line 5—5 of Figure 3.

Figure 6 is a cross sectional view on line 6—6 of Figure 3.

Figure 7 is a vertical sectional view on line 7—7 of Figure 5.

Referring more especially to the drawings, 55 1, 2 and 3 designate the inner, outer and intermediate sections of the music roll, purse and carrying bag. It will be noted that the inner and intermediate sections are substantially of the same dimensions and are stitched together as shown at 4 and provided with a binding 5, for connecting the side and bottom edges. The upper edges of these sections have a stitched binding 7.

The outer section 2 is of the same width 60 as the inner and intermediate sections, but is longer than the inner and intermediate sections, particularly at the upper end, thereby providing an extension 8, which constitutes a closure. The marginal edge of the section 2 has a binding 9 stitched thereto.

Strips 11 of material, preferably leather 65 are also fastened to the section 2 by means of the marginal binding, that is to the side and bottom edges. These strips 11 are first stitched together at certain of their ends as indicated at 12, so as to provide a U-shaped section of material carried by the section 2. This U-shaped section is stitched 70 as at 13 to the intermediate section, a short distance inwardly from the marginal edge thereof. By this construction it will be noted that the several sections of the music roll,

purse and carrying bag are connected in a bellows fashion, so that when the device is used as a carrying bag, the several sections may be distended considerable distance, so 5 that the compartments may be opened very wide, and thereby give considerable space, for the reception of articles to be carried, especially when shopping.

It will also be noted that the adjacent 10 faces of the inner and intermediate sections have a lining 14, while the inner face of the outer section 2 and the inner face of the closure are provided with a lining 15.

The upper portion of the inner face of 15 the intermediate section has stitched thereto a thickness of material 16, which causes a purse compartment 17 to be formed, the inner face of such section having a lining 18.

The lower portion of the outer face of the 20 outer section 2 is provided with a plurality of male members 19 of snap fasteners, while the upper portion of one face of the inner section is provided with a plurality of male members 20 of snap fasteners, preferably 25 arranged in pairs. The closure has a plurality of female members 21 of snap fasteners, to engage either the male members of the lower portion of the outer face of the outer section, or either set of male 30 members of the upper portion of one face of the inner section, so that the closure may be used for closing the device when used as a music roll and purse, or close the device when used as a carrying bag. It is obvious 35 that by the provision of the two sets of male members on the upper portion of one face of the inner section, so that the closure may be fastened in one or more positions, so as to permit the device when used as a 40 carrying bag to hold more or less at the top of the bag, when the closure is fastened.

The exterior of the closure at the point where it folds has plates 22 and holding rings 23, to which the handle 24 is connected.

These plates are riveted to the closure, and 45 to a stiffening member 25, which is interposed between the lining and the material of the closure.

When the device is folded on itself as indicated in Figures 1 and 2, it may be used 50 as a music roll, or half portions of the compartments may be used as purse compartments. When the device is open as shown in Figure 3, it is obvious that it may be used 55 as a carrying bag for shopping purposes.

The invention having been set forth, what is claimed as being useful is:—

In a music roll, purse and carrying bag, inner, outer and intermediate walls, the inner and intermediate walls being joined at 60 their side and bottom edges, a U-shaped member corresponding in shape to the marginal edges of the walls and being stitched to the inner face of the outer wall adjacent its side and bottom edges, the inner marginal edge of the U-shaped member being stitched to the intermediate wall, thereby causing to be formed a plurality of widely distensible compartments, and at the same time providing bellows connections between the several 65 walls, a plurality of sets of fastener members carried by the upper portion of the inner face of the inner wall, fastener members carried by the lower portion of the exterior face of the outer wall, a closure common for 70 closing the several compartments and at the same time holding the lower half of the device folded when used as a music roll, said closure having fastener members common to 75 both sets of fasteners carried by the inner 80 and outer walls.

In witness whereof, in the presence of two witnesses, the inventor's signature is hereunto affixed.

JOS. P. LA ROCHE.
